US0D1058858S

(12) **United States Design Patent** (10) **Patent No.:** **US D1,058,858 S**
(45) **Date of Patent:** **** Jan. 21, 2025**

(54) **BEAD TRIM**

(71) Applicant: **Alabama Metal Industries Corporation**, Birmingham, AL (US)

(72) Inventor: **Gary George Baltz, Jr.**, Mountain Brook, AL (US)

(73) Assignee: **Alabama Metal Industries Corporation**, Birmingham, AL (US)

(**) Term: **15 Years**

(21) Appl. No.: **29/864,273**

(22) Filed: **May 17, 2022**

(51) LOC (15) Cl. **25-01**

(52) U.S. Cl.

USPC **D25/102**

(58) **Field of Classification Search**

USPC D25/102, 136, 164, 119–126, 48.1, 48.2, D25/55, 60, 132; D8/349, 354, 380; D23/389

CPC E04F 13/0826; E04F 19/02; E04F 19/04; E04F 2019/0413; E04B 9/00; E06B 1/70; E06B 1/34; E06B 1/524

(57) **CLAIM**

The ornamental design for a bead trim as shown and described.

DESCRIPTION

FIG. 1 is a perspective view of the bead trim; FIG. 2 is an end view of the bead trim; FIG. 3 is another end view of the bead trim; FIG. 4 is a rear side view of the bead trim; FIG. 5 is a front side view of the bead trim; FIG. 6 is a top view of the bead trim; and, FIG. 7 is a bottom view of the bead trim.

The broken lines shown in the drawings represent portions of the bead trim and form no part of the claimed design. The drawings contain symbolic break lines in FIG. 1 and FIGS. 4–7. The break lines and any portions of the bead trim between the break lines form no part of the claimed design.

1 Claim, 7 Drawing Sheets
